United States Patent Office

Des. 176,471
Patented Dec. 27, 1955

176,471

TRIPOD

Raymond Mooney, Skokie, Ill., assignor to Quick-Set,
Incorporated, Skokie, Ill., a corporation of Illinois

Application April 13, 1955, Serial No. 35,493

Term of patent 14 years

(Cl. D61—1)

Fig. 1.

Fig. 2.

Fig. 3.

Fig. 4.

Fig. 5.

Fig. 6.

Figure 1 is a view in side elevation of a tripod embodying my design.

Figure 2 is an end view of the tripod shown in Figure 1.

Figure 3 is a view in side elevation of the tripod taken from the opposite side shown in Figure 1.

Figure 4 is an end view of the tripod taken from the opposite end shown in Figure 2.

Figure 5 is a plan view of the tripod shown in Figure 1.

Figure 6 is an enlarged view of the tripod shown in Figure 3.

The dominant features of my design reside in the portions shown in full lines.

The legs and elevator are broken away in Figures 1 to 5 for convenience of illustration only.

I claim:

The ornamental design for a tripod, substantially as shown and described.
